(57) **CLAIM**

The ornamental design for a pen, as shown and described.

DESCRIPTION

FIG. 1 is a perspective view of a pen showing my new design;
FIG. 2 is a front elevational view thereof;

FIG. 3 is a left side elevational view thereof; the right side
elevational view is a mirror image of the left side;

FIG. 4 is a rear elevational view thereof;

FIG. 5 is a top plan view thereof;

FIG. 6 is a bottom plan view thereof; and,

FIG. 7 is an exploded perspective view thereof.

The broken line showing in FIGS. 1 to 7 is for illustrative
purposes only and forms no part of the claimed design.
